UNITED STATES PATENT OFFICE.

JOSEPH WILCOX, OF CANTON, PENNSYLVANIA.

IMPROVEMENT IN CAR-COUPINGS.

Specification forming part of Letters Patent No. 141,846, dated August 12, 1873; application filed February 28, 1873.

To all whom it may concern:

Be it known that I, JOSEPH WILCOX, of Canton, in the county of Bradford and State of Pennsylvania, have invented certain new and useful Improvements in Car-Coupling; and I do hereby declare that the following is a full, clear, and exact description thereof, reference being had to the accompanying drawings and to the letters of reference marked thereon, which form a part of this specification.

The nature of my invention consists in the construction and arrangement of a car-coupling, as will be hereinafter more fully set forth.

In order to enable others skilled in the art to which my invention appertains to make and use the same, I will now proceed to describe its construction and operation, referring to the annexed drawing, in which—

Figure 1 is a side elevation of my car-coupling, showing one of the draw-heads in longitudinal vertical section. Fig. 2 is a horizontal section of one of the draw-heads.

My car-coupling is simple; and consists merely in the application of three springs and a tube to an ordinary draw-head, with the usual pin and link, and can readily be attached to any draw-head now in use, the object being to make the same self-coupling, and to hold the link in proper position for coupling.

A A represent two draw-heads of any of the known and usual forms. B B are the coupling-pins, and C is the coupling-link. In each draw-head A are two springs, D D, fastened one to each side of the mouth or entrance of the draw-head, and extending toward the rear. The front portions of the springs D D are slightly curved, as shown in Fig. 2, while the rear portions are straight; and along the upper edge of each of said straight parts is

an inward-projecting flange, a. In the top of the mouth of the draw-head is fastened another spring, E, which extends inward and downward, as shown more particularly in Fig. 1. On top of each draw-head is a short tube or perforated brace, b, through which the coupling-pin B passes.

When the pin B is drawn up above the springs D D, the inner ends of said springs close, so that the flanges a a form a support for the pin, upon which it can rest, it being held in a proper position by the tube or brace b. When the link C enters the draw-head it passes under the inner end of the spring E, and presses the inner ends of the springs D D apart, till the flanges a a become so far separated that the pin B will fall down of its own weight and couple. The spring E holds the link C in a horizontal position, so that it will enter the opposite draw-head without being guided, as usual, by hand, thus doing away with one of the most fruitful sources of accidents in coupling cars.

Having thus fully described my invention, what I claim as new, and desire to secure by Letters Patent, is—

The spring E, attached to the front part of the draw-head, extending backward and resting upon the link C, in combination with the springs D D, having flanges a a, and pin B, all constructed and arranged for operation as set forth.

In testimony that I claim the foregoing as my own I affix my signature in presence of two witnesses.

JOSEPH WILCOX.
